CLAIM

The ornamental design for a playground amusement device, as shown and described.

DESCRIPTION

FIG. 1 is a top and front, right side perspective view of a playground amusement device showing our new design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a top and front, right side perspective view thereof shown with a first mounting structure; and, FIG. 9 is a top and front, right side perspective view thereof shown with a second mounting structure. The broken lines showing mounting structures in FIGS. 8-9 illustrate environment and form no part of the claimed design. The remaining broken lines in the drawings illustrate portions of the playground amusement device that form no part of the claimed design.
